(57) **CLAIM**

The ornamental design for a surface configuration of a
rollover bar for a vehicle, as shown and described.

DESCRIPTION

FIG. 1 is a rear view of a surface configuration of a
rollover bar for a vehicle according to my novel design;

FIG. 2 is a rear perspective view of the surface configuration
of a rollover bar for a vehicle according to my novel design;

FIG. 3 is a front perspective view of the surface configura-
tion of a rollover bar for a vehicle according to my novel
design; and,

FIG. 4 is an elevated side view of the surface configuration
of a rollover bar for a vehicle according to my novel design.
The broken lines are for illustrative purposes only and form
no part of the claimed design. Also enclosed is a set of
photographs of an embodiment of the design.

1 Claim, 2 Drawing Sheets
